CLAIM

The ornamental design for a symbol display for a gaming device, as shown and described.

DESCRIPTION

FIG. 1 is a front perspective view of the symbol display for a gaming device of our new design, that portion of the gaming device shown in phantom is not part of the design sought to be patented and is provided for environmental purposes only;

FIG. 2 is a rear elevation view thereof;

FIG. 3 is a front elevational view thereof;

FIG. 4 is a top plan view thereof;

FIG. 5 is a bottom plan view thereof;

FIG. 6 is a left side elevational view thereof; and,

FIG. 7 is a right side elevational view thereof.
